GEORGE GODDU, OF WINCHESTER, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WORK-SUPPORT-CONTROLLING MECHANISM.

1,356,523.

Specification of Letters Patent. Patented Oct. 26, 1920.

Application filed February 9, 1915. Serial No. 7,083.

To all whom it may concern:

Be it known that I, GEORGE GODDU, a citizen of the United States, residing at Winchester, in the county of Middlesex and 5 State of Massachusetts, have invented certain Improvements in Work-Support-Controlling Mechanism, of which the following description, in connection with the accompanying drawings, is a specification, like 10 reference characters on the drawings indicating like parts in the several figures.

This invention relates to work supports and to work support controlling mechanisms and is herein shown as embodied in 15 a work support and its controlling mechanism of the type which is particularly adapted for use in machines for inserting fastenings in boots or shoes. It will be understood, however, that the invention is not 20 restricted to the illustrated embodiment or to the illustrated uses.

The machine in which the invention is herein shown as incorporated is of the type which employs an awl to form a fastening 25 receiving opening in the work, the awl then operating to feed the work into position to have the fastening inserted in said opening. In such machines it is important that the work be firmly supported, both at the time 30 the awl is forced into the work to form the fastening receiving opening and at the time the fastening is driven. Between these operations it is desirable that the pressure upon the work be diminished or altogether 35 relieved in order that the awl may feed the work easily and without danger of injury to the awl, such as bending or breaking.

Machines of the type in which the invention is shown as incorporated are operated 40 at comparatively high speeds; that is, at speeds which range from 400 to 600 fastening inserting operations per minute. It is essential, therefore, that the control of the work support in a machine of this type be 45 substantially positive in order to insure the proper coöperation between the work support and the fastening inserting mechanism. To provide for the quick accommodation of the work support to variations in the thickness 50 of the work and at the same time to accelerate the return of the work support to its supporting position after the work feeding operation, and sometimes to afford a strong yielding support for the fastening

inserting operation, it is customary to employ a strong spring in connection with the work support and its releasing mechanism. In many work support controlling mechanisms in common use this spring is so arranged that it maintains the work support 60 normally in work clamping position, a treadle being connected to the work support to depress it against the spring when it is desired to remove the work or to place work upon the work support and a second treadle 65 being provided to control the starting and stopping of the machine. Such work support operating and controlling mechanism is shown and described in United States Letters Patent to L. Goddu, No. 265,227, September 26, 1882, and an object of the present invention is to improve the construction and to simplify the operation of work supports of the general type disclosed in said Letters Patent. To this end the invention aims to 75 provide for the control, from a single treadle, of the movement of the work support between work receiving position and work clamping position and the starting and stopping of the machine, without sacrificing 80 any of the advantages of firm support at proper times in the operation of the machine which have made the earlier construction so satisfactory, as attested by its common use.

More particularly the invention aims to provide work support controlling mechanism of the single treadle type which can readily be applied to, or incorporated in, machines already in use.

An important feature of the invention is the provision, in work support controlling mechanism of the single treadle type, of novel means controlled from said treadle for preventing premature lowering of the 95 work support.

In accordance with another feature of the invention, the treadle controlled means for preventing premature lowering of the horn is constructed and arranged to provide a 100 rigid support for the work support when it is in its operative position and, preferably and as shown, to be moved into its supporting position after the work support has been raised into final work clamping position but 105 before the machine is started.

Other important features and objects of the invention will appear from the follow-

ing description and claims when considered in connection with the accompanying drawings.

In the accompanying drawings,

5 Figure 1 shows in side elevation, with parts broken away to make clearer the construction of parts otherwise concealed, a machine of the type illustrated in United States Letters Patent to L. Goddu, No. 10 490,624, January 24, 1893, having incorporated therein the work support controlling mechanism of the present invention, the parts being in inoperative position;

15 Fig. 2 is a detail elevation showing the parts in operative position.

The mechanism in the head of the machine for controlling the starting and stopping of the machine, and the mechanism in the head of the machine for operating the 20 connections to the work support by which the work support is depressed for the feeding of the work, are substantially identical with those shown and described in Letters Patent No. 490,624, hereinabove referred to, 25 the wedge C³ at the upper end of a rod C⁴, the cam disk C⁶ having a beveled periphery engaged by a brake B¹ and receiving in a cam groove in its face a roller upon the lever C⁷ to which is connected the rod C⁸ 30 by which the pawl carrying slide d² is operated, being substantially the same as the parts indicated by corresponding reference characters in said Letters Patent, the pawl carrying slide d² being shown and described in the earlier Letters Patent hereinabove referred to, No. 265,227. As in 35 said earlier Letters Patent, the slide d² carries a pawl d adapted to engage one of the teeth d⁵ of a ratchet slide which is connected by a rod d⁶ to a lever C⁹ having connections at its other end to the work support, whereby the work support may be depressed during the work feeding operation, the pawl d being thrown out of engagement 40 with the ratchet teeth d⁵ upon the return movement of the slide d² by engagement with the cam block d⁷ and being yieldingly maintained in engagement with the ratchet teeth d⁵ by a spring plunger d⁸. The parts 45 thus far described, with the exception of the rods d⁶ and C⁴, are substantially identical with the parts indicated by the corresponding reference characters in said Letters Patent No. 265,227.

50 To facilitate the removal of the work from the work support and the placing of the work upon the work support the invention aims to provide means for causing the work support to move into work receiving position when the machine stops and for moving it again into work clamping position before the machine starts, this means being arranged to be controlled from a single treadle. The work support, which is 55 herein shown as of the horn type, comprises

a horn 2, which operates to clamp the work against a work abutment 4 during the forming of the awl hole and during the insertion of the nail or other fastening, the horn being yieldingly held in work clamping position by a strong spring 6 surrounding the rod d⁶ and confined between a boss 8, which serves as a guide for said rod upon the rear of the post 10 of the machine, and a collar 12 screwed upon said rod, the pressure of 70 the spring 6 being transmitted to the horn 2 through breakable connections now to be described.

The horn 2 is carried upon a horn post 14 arranged to slide vertically in a guide 16 80 formed upon the machine frame, the horn post 14 being connected at its lower end, by means of a rod 18, to a slide 20 guided in an opening in a horizontal portion 22 of the machine base, the slide 20 being arranged 85 to move vertically in said opening but being limited in its downward movement by a stop washer 24 confined against the upper end of said slide by a nut 26 upon the rod 18. The lever C⁹ is fulcrumed upon a cross 90 shaft 28 carried by depending ears 30 in the machine base, and also fulcrumed upon this cross shaft is a treadle lever 32 which is pivotally connected at its rear end to a rod 34 guided in a guideway 36 in which 95 the lower end of the rod C⁴ is guided, these rods having their ends normally separated when the machine is at rest, the spring 38, which surrounds said rod 34 and is confined between the rear end of the treadle lever 100 32 and the lower part of that portion of the machine frame in which the guide 36 is formed, tending to keep the forward end of the treadle lever 32 raised and the rear end depressed, thus maintaining the upper 105 end of the rod 34 out of engagement with the lower end of the rod C⁴. A light spring 40, confined between a collar 42 upon the rod C⁴ and the upper end of the bracket in which the guide 36 is formed, prevents the rod C⁴ from dropping, under the action 110 of gravity, into engagement with the rod 34. The treadle lever 32 has formed upon it a depending arm 44 which makes of the treadle lever a bell crank by which a toggle 115 may be operated to raise the horn 2 into work supporting position before the machine is started, the breaking of the toggle after the treadle has been released to stop the machine operating to lower the horn 120 into work receiving position.

The illustrated toggle mechanism comprises a link 46 which straddles the slide 20 and has a pivotal connection 48 with said slide, the ends of said pivot 48 being 125 guided in elongated slots 50 in the slide 20 and normally positioned to bear against the slide 20 at the upper ends of the slots 50. The forked lower link 54 of the toggle is pivotally connected to the upper link at 130

52 and is also pivotally connected with the lever C^o at 58. The lower link 54 of the toggle extends below its pivotal connection with the lever C^o and has a further pivotal 5 connection through a link 57 with the arm 44 of the treadle lever 32. A stop 59 extending between the two parts of the link 54 brings up against the side face of an extension 70 upon the slide 20 when the 10 toggle has been moved into straightened, or slightly past straightened position, in order to prevent the toggle from breaking too far in the other direction.

To provide means for affording a more 15 rigid support for the horn and also means for preventing the horn from dropping before the machine has completed its operation upon the work, a stop member 56 is pivoted at 58 to the lever C^o and is located 20 between the two sides of the link 54. A pin 60 carried by said stop member extends into the slots 62 in the link 54 and limits the relative movement about the axis 58 of the link 54 and the stop member 56. A 25 spring 64 connected to the link 54 and engaging the pin 60 tends to keep the link 54 and stop member 56 in the relative positions shown in Fig. 1. The stop member 56 has a stop face 66 at its upper end 30 adapted to coöperate with a similar stop face 68 upon the lower end of the extension member 70 of the slide 20, the side of said member 56 adjacent to the extension 70 in Fig. 1 of the drawings being adapted to co- 35 operate with a lateral stop 73 upon the extension member 70. To permit relative movement of the end faces 66 and 68 of the parts 56 and 70 into and out of engagement without binding as the member 56 turns 40 about its pivot 58 the end face 66 of the member 56 is slightly inclined, and the end face 68 of the extension 70 is correspondingly inclined.

The stop recited in combination with the 45 work support in certain of the claims at the end of this specification, finds its specific embodiment in the illustrative machine in the stop member 56. It is to be understood, however, that the term "stop" as used in 50 these claims covers any device arranged to be interposed in the path of the work support to act by its presence as an obstruction to movement of the work support. When interposed below the work support, such a 55 stop device serves as a support for the work support.

The operation of the mechanism thus far described is as follows: The parts being in the position shown in Fig. 1, the operator 60 places the work upon the horn 2 and then depresses the treadle 32 causing it to rock in a clockwise direction about the fulcrum shaft 28 (see Fig. 1). During the first part 65 of the movement of the treadle the toggle link 54 will be rocked about the pivot 58

upon the forward end of the lever C^o , thus tending to straighten the toggle to raise the slide 20 until the horn 2 clamps the work against the foot plate or work abutment 4. When the work is thus clamped further 70 movement of the toggle toward straightened position will depress the pivot 58, thus raising the rear end of the lever C^o and compressing the spring 6 between the collar 12 and the post 8. During this straightening 75 movement of the toggle and until the upper end face 66 of the member 56 has been moved below the lower end face 68 of the extension 70, or vice versa, there will be a relative movement of the member 56 and 80 the toggle link 54 about the pivot 58 against the tension of the spring 64. When the toggle is substantially in straightened position the pivots 58 and 48 will be separated sufficiently so that the end faces 66 and 68 85 will have passed by each other, thus permitting the spring 64 to move the member 56, the pin 60 of which is now near the left hand end of the slot 62, in a clockwise direction about the pivot 58 to bring the 90 end face 66 beneath the end face 68, the side of the member 56 abutting against the stop 73 upon the extension 70. Further movement of the treadle operates to break 95 the toggle slightly to the other side and to draw the end faces 66 and 68 into engagement with each other, the stop 59, which abuts against the side of the extension 70, serving to limit the breaking movement of the toggle upon this side. During the last 100 part of the movement of the treadle the upper end of the rod 34 has engaged the lower end of the rod C^4 and raised the wedge C^3 into clutch operating position thus starting the machine after the work support has been brought into work clamping 105 position, spring pressure has been applied to the work support and a positive rigid connection between the lever C^o and the work support has been effected.

The machine having been started the awl enters the work in the usual manner and is then moved to feed the work over the horn 2, but before this feeding movement begins the horn 2 is depressed by the "horn release" 115 or work support releasing mechanism hereinabove described. The operation of this mechanism is substantially identical with that described in Letters Patent No. 265,227, hereinabove referred to.

The required number of operations having been performed upon the work the operator releases the treadle 32 and the spring 38 immediately rocks it in a counter-clockwise direction about the fulcrum shaft 28, 125 the first part of the movement of the treadle serving to move the upper end of the rod 34 out of engagement with the lower end of the rod C^4 , thus permitting the wedge C^3 to move out of clutch operating position, where- 130

upon the machine stops at the end of a complete operation, as more fully set forth in Letters Patent No. 490,624, hereinabove referred to.

- 5 Further movement of the treadle serves to break the toggle into the position shown in Fig. 1, the first part of the movement of the treadle slightly depressing the pivot 58 and bringing the toggle into its straightened position and also effecting a relative movement of the link 54 and the member 56 so that the pin 60 is brought into the right hand end of the slot 62, whereupon, during the further breaking movement of the toggle, the link 54 and the member 56 move together, the end face 66 of said member being moved out from its position under the end face 68 of the extension 70, by the engagement of the right hand end of the slot 62 with the pin 60 on the member 56, thus permitting the horn to drop as the treadle rises and the toggle is broken into the position shown in Fig. 1. During this further breaking movement of the toggle, the toggle link 46 moves freely downwardly relatively to the slide 20 in the slots 50, thus permitting the withdrawing movement of the member 56 by the toggle link 54, the spring 38 being sufficiently strong to overcome the pressure upon the end face 66 caused by the weight of the horn, and the inclinations of the faces 66 and 68 preventing interlocking or binding of those faces. It will be seen that the slot 62 provides lost motion to prevent the horn from being lowered until the treadle has moved sufficiently to throw the wedge C² into clutch releasing position so as to insure stopping of the machine before the horn is lowered.
- 40 To prevent the expansion of the spring 6 to the limit when the toggle is broken and the work support is lowered and also to prevent interference with the lowering operation, a stop 74 is provided upon the lever C², this stop being threaded through a cross piece 72 which straddles the leg 71 of the machine base and engages a stop surface 75 formed upon said leg.
- It will be noted that the lost motion between the rods 34 and C² is sufficient to permit the raising of the work support by the straightening of the toggle 46, 54, and the interposition of the stop 56, before said rods engage and that the further lost motion provided by the pin and slot connection between the stop 56 and the link 54 is sufficient to allow the clutch to be operated to start the machine after the work support is in work supporting position.
- 55 It will also be noted that the link 57 is in such relation to the lever C² that it does not interfere with the intermittent depression of the work support for the feeding of the work between the successive operations thereon.

Having fully described my invention, what I claim as new and desire to secure by Letters Patent of the United States is:

1. In a machine of the class described, a work abutment, a work support movable relatively to said abutment to clamp the work between the work support and the abutment, means for raising said work support to apply final work clamping pressure, starting and stopping means, a single treadle for operating said work support raising means and said starting and stopping means to perform the operations described, a stop for preventing premature lowering of said work support, and means whereby said stop is controlled from said treadle.
2. In a machine of the class described, a stationary work abutment, a work support, a treadle, means operated by said treadle for raising and lowering said work support between a work receiving position and a final work clamping position, positive connections between said treadle and said raising and lowering means, a stop for preventing premature lowering of said work support, and lost motion connections between said treadle and said stop.
3. In a machine of the class described, a work support, an abutment between which and said work support the work is clamped, means for raising said work support to apply final work clamping pressure, clutch operating means, a treadle, positive connections between said work support raising means and said treadle for operating said means, lost motion connections between said treadle and said clutch operating means, constructed and arranged to cause said work support to be fully raised before the machine is started, a stop for preventing premature lowering of said work support, and lost motion connections between said treadle and said stop.
4. In a machine of the class described, a work support, a spring, work support raising means constructed to apply the pressure of said spring to said work support, a treadle, positive connections between said treadle and said raising means for operating said raising means, a stop for preventing premature lowering of said work support, and lost motion connections between said treadle and said stop.
5. In a machine of the class described, a work support, starting and stopping means comprising a treadle, a toggle for raising and lowering said work support, positive connections between said toggle and said treadle, a stop for preventing premature lowering of said work support, and lost motion connections between said stop and said treadle.
6. In a machine of the class described, a work support, starting and stopping means

comprising a treadle, a toggle for raising and lowering said work support, means for positively straightening and breaking said toggle, a stop for preventing premature 5 lowering of said work support, and lost motion connections between said stop and said treadle for operating said stop.

7. In a machine of the class described, a work support, a toggle through which said 10 work support is raised and lowered, a stop for preventing premature lowering of said work support, and lost motion connections between said toggle and said stop for operating said stop.

15 8. In a machine of the class described, a work support, a spring, means comprising a pair of toggle members for bringing spring pressure to bear upon said work support, and means acting when said toggle 20 is straightened to establish a supporting connection independent of the toggle members between the points connected by said toggle.

9. In a machine of the class described, a 25 work support, starting and stopping means comprising a treadle, connections between said work support and said treadle constructed and arranged to cause the work support to be raised to apply final work clamping pressure before the machine is started, and means also operated from said treadle 30 for locking said work support in said work supporting position.

10. In a machine of the class described, a 35 work support movable between work receiving position and work supporting position, a toggle arranged to be straightened to effect the movement of the work support into supporting position and to be broken 40 to permit the movement into receiving position, means for straightening and breaking said toggle, and means independent of the members of the toggle for establishing a work supporting connection between the 45 points connected by said toggle.

11. In a machine of the class described, a work support, starting and stopping means comprising a treadle, a toggle for raising and lowering said work support, positive 50 connections between said treadle and said toggle, a spring arranged to be compressed by the straightening of said toggle to bring spring pressure to bear upon the work support, a stop for preventing premature 55 removal of said spring pressure, and lost motion connections between said stop and said treadle.

12. In a machine of the class described, a work support, a spring for maintaining said 60 work support in operative position, means for intermittently depressing said work support to permit the work to be fed there- over, connections between said work sup- port and said depressing means comprising 65 a toggle, and means for maintaining the

parts connected by said toggle in extended relation.

13. In a machine of the class described, the combination with a work support, and means for intermittently depressing said 70 work support, of means for moving said work support from work receiving position to work clamping position before the machine is started comprising a treadle operated toggle, means for maintaining in ex- 75 tended relation the parts connected by said toggle, and lost motion connections between said last named means and said toggle constructed and arranged to prevent premature lowering of said work support. 80

14. In a machine of the class described, a work support, a fixed abutment, means for raising and lowering said work support into and out of position to clamp the work against said abutment, a stop arranged to 85 be moved into position beneath said work support before the machine is started, and lost motion connections between said stop and said raising and lowering means.

15. In a machine of the class described, a 90 work support, a treadle, a toggle for rais- ing and lowering said work support, operat- ing connections between said toggle and said treadle, a stop arranged to be moved into position beneath said work support when 95 said work support is in raised condition, and operating connections between said stop and said treadle.

16. In a machine of the class described, a 100 work support, a toggle for raising and lowering said work support, a stop arranged to be moved into position beneath said work support when the work support is raised, and yielding lost motion connections 105 between said toggle and said stop for mov- ing said stop into and out of operative posi- tion.

17. In a machine of the class described, a 110 work support, a toggle by which said work support is raised and lowered, a stop ar- ranged to be moved into position beneath 115 said work support when said toggle is straightened, said stop and said work sup- port being arranged to be brought into oper- ative engagement by a further movement of said toggle out of straightened position.

18. In a machine of the class described, a 120 work support, a spring, means for raising and lowering said work support construct- ed to bring the pressure of the spring to bear upon said work support when raised and to remove said pressure when said sup- port is lowered, a stop for preventing the removal of the spring pressure when the work support is raised, and lost motion con- nections between said raising and lowering means and said stop for moving said stop into and out of operative position. 125

19. In a machine of the class described, a 130 work support, a treadle for raising and

lowering said work support, an abutment arranged to be brought into operative position beneath said work support when it is raised to lock it in raised position, and 5 means connected to said treadle for yieldingly pressing said abutment toward operative position as the work support is being raised.

20. In a machine of the class described, a 10 work support, means for raising and lowering said work support, a stop normally at one side of the lowered work support arranged to be moved into position beneath the work support when the work support is raised, and means connected to said raising means for yieldingly pressing the stop against the side of said work support as it is being raised.

21. In a machine of the class described, a 15 work support, a toggle arranged to be straightened to move said work support into work supporting position and to be broken to permit said work support to move into work receiving position, other means arranged to be moved into position as said toggle is straightened to lock said work support in work supporting position before the machine is started, and direct lost motion connections between said last-mentioned 25 means and said toggle so constructed and arranged that said toggle exercises positive control over said last-mentioned means.

22. In a machine of the class described, a 30 work support, starting and stopping means comprising a treadle, connections between said work support and said treadle comprising a toggle arranged to be straightened by said treadle to move said work support into supporting position and to be broken 35 to permit said work support to move into receiving position, means for limiting the movement of said toggle by said treadle, and means controlled directly by said toggle for preventing said work support from being lowered until said treadle has effected a 40 partial return movement of said toggle.

23. In a machine of the class described, a 45 work support, starting and stopping means comprising a treadle, connections between said work support and said treadle whereby the work support is raised to apply final work-clamping pressure before the machine is started, means for thereafter locking said work support in work supporting position, and lost motion connections between said 50 treadle and said locking means constructed and arranged to prevent unlocking of said work support before the machine is stopped.

24. In a machine of the class described, a 60 work support, starting and stopping means comprising a treadle, positive connections between said work support and said treadle whereby the work support is raised before the machine is started, means for locking 65 said work support in work supporting posi-

tion, and lost motion connections between said treadle and said locking means whereby said treadle may be moved to stop the machine before said work support is unlocked.

25. In a machine of the class described, a 70 work support, a spring, starting and stopping means comprising a treadle, a toggle arranged to be straightened by said treadle before the machine is started to cause said spring to act upon said work support, and 75 means moved into position as said toggle is straightened for preventing the removal of the action of said spring upon said work support before the machine completes its 80 operation upon the work.

26. In a machine of the class described, a 85 work support, a spring, means comprising a toggle and a member upon which one link of said toggle is pivoted for raising said work support and compressing said spring, a stop for preventing premature lowering of said work support having a pivot upon said member co-axial with said toggle link pivot, and lost motion connections between 90 said toggle link and said stop for operating said stop.

27. In a machine of the class described, a 95 work support, starting and stopping means comprising a clutch operating means and a treadle, connections between said work support and said treadle comprising a toggle by which said work support may be raised and lowered, connections between said treadle and said clutch operating means having provision for lost motion whereby said 100 toggle may operate to raise said work support while said lost motion is being taken up, means for locking said work support in raised position, and connections between said treadle and said locking means having 105 provision for lost motion after said first-mentioned lost motion has been taken up.

28. In a machine of the class described, a 110 work support, starting and stopping means comprising a clutch operating means and a treadle, connections between said work support and said treadle whereby the work support is raised by said treadle, connections between said treadle and said clutch operating means having provision for lost motion 115 whereby the work support is raised before the machine is started, and means for locking said work support in raised position also so connected to said treadle as to be brought into operative position before the 120 machine is started.

29. In a machine of the class described, a 125 work support movable between a work receiving position and a work supporting position, means operating upon said work support when in work supporting position for intermittently depressing said support to points between said positions to permit the work to be fed, means for moving said work support between its receiving and support- 130

ing positions comprising a toggle in the connections between said support and said depressing means, and other means for maintaining said work support in work supporting position.

30. In a machine of the class described, a stationary abutment, a work support movable upwardly for pressing the work against the abutment, starting and stopping mechanism comprising a treadle, and means operated from said treadle for providing a rigid support for the work support, said means being operative, after the application of the maximum work-clamping pressure 10 and before the machine is started, for holding the work support in final work-supporting position.

31. In a machine of the class described, a stationary abutment, a work support for 20 pressing the work against the abutment, starting and stopping mechanism comprising a treadle, connections between the work support and the treadle constructed and arranged to cause the work support to be 25 raised into final work supporting position before the machine is started, and means also operated from said treadle for locking the work support in said work supporting position.

30. 32. In a machine of the class described, a work abutment, a work support movable relatively to said abutment to clamp the work between the work support and the abutment, means for moving said work support to apply final work clamping pressure, starting and stopping means, a single member for operating said work support moving means and said starting and stopping means to perform the operations described, a stop 35 for preventing premature work-releasing movement of said work support, and means whereby said stop is controlled from said member.

33. In a machine of the class described, a 45 work support, a spring, work support moving means constructed to apply the pressure of said spring to said work support, a lever, positive connections between said lever and said moving means for operating said moving means, a stop for preventing premature work-releasing movement of said work support, and lost motion connections between 50 said lever and said stop.

34. In a machine of the class described, a movable work support, starting and stopping means comprising a treadle, connections between said work support and said treadle whereby the work support is raised before the machine is started, and means comprising a member arranged to be interposed in the path of the movable work support for locking said work support in work supporting position constructed and arranged in such a way that the treadle may be moved to stop the machine before the work support is unlocked. 55

35. In a machine of the class described, a work support, starting and stopping mechanism comprising a treadle, means for raising the work support to apply final work-clamping pressure, and connections between 60 said work support and said treadle constructed and arranged to provide a rigid support for the work support after the application of said pressure and before the 65 starting of the machine. 70

36. In a machine of the class described, a work support, starting and stopping mechanism comprising a treadle, means comprising a toggle for raising the work support, 80 said toggle being movable beyond center, and connections between said work support and said treadle constructed and arranged to provide a rigid support for the work support after said toggle moves beyond 85 center.

37. In a machine of the class described, a work support, starting and stopping mechanism comprising a treadle, means comprising a toggle for raising the work support, 90 said toggle being movable beyond center, and connections between said work support and said treadle constructed and arranged to provide a rigid support for the work support, said mechanism being operative to 95 start the machine while the toggle moves beyond center.

In testimony whereof I have signed my name to this specification in the presence of two subscribing witnesses.

GEORGE GODDU.
